(57) **CLAIM**

The ornamental design for a folding chair frame as shown and described.

DESCRIPTION

FIG. 1 is a top, front, and right side perspective view of a folding chair frame showing my new design in an open configuration;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2;

FIG. 11 is a top, front, and right side perspective view showing the folding chair frame in an environment of use; and,

FIG. 12 is a top perspective view showing the folding chair frame of FIG. 1 in a closed configuration.

The evenly dashed broken lines illustrating the seating material in FIG. 11 show environment that forms no part of the claimed design. All other evenly dashed broken lines illustrate portions of the folding chair frame which form no part of the claimed design.

The dash-dot broken lines illustrate the boundary of the enlarged views and form no part of the claimed design.

1 Claim, 12 Drawing Sheets
